UNITED STATES PATENT OFFICE.

HIRAM G. FILSON, OF NEW CUMBERLAND, WEST VIRGINIA.

ADJUSTABLE EAVES-TROUGH BOX.

SPECIFICATION forming part of Letters Patent No. 242,291, dated May 31, 1881.

Application filed March 14, 1881. (No model.)

To all whom it may concern:

Be it known that I, H. G. FILSON, a citizen of the United States, resident at New Cumberland, in the county of Hancock and State of 5 West Virginia, have invented certain new and useful Improvements in Adjustable Eaves-Trough Boxes; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 Figure 1 is a representation of a side view. Fig. 2 is a cross-section, and Fig. 3 is a detail view.

20 This invention relates to adjustable eaves-trough boxes; and it consists in the improved features of construction and combination hereinafter fully described, and particularly pointed out in the claims.

25 In the annexed drawings, A is a trough, angular in cross-section, consisting of bottom B and sides C C'.

Attached transversely to the bottom, near the ends, are the rockers D D, between the feet d of which are secured the right-angled bases of two standards, E E', the base e of the 30 former being rigidly secured, and the base e' of the latter slotted at e² and held adjustably by a pin or screw, F. These standards pass in opposite directions, and their uprights e³ come up on the outside of and hold the sides C C',

35 said uprights having the slots e⁴.

g g are recesses in the outside of sides C C' just where the uprights e³ come, and in these are secured the plates G G, in which latter are formed the threaded recesses g' g', adapted to 40 receive the screws H H, passing through the

slots e⁴, by which the sides are adjustable within the standards or uprights.

On the inside of the side C, near its top, is made the longitudinal angular groove I. Perpendicular in the side C' are formed the circular seats k passing therethrough. In these seats are placed the shanks l of catches L, whose heads l' rest upon the top of said side. Within these seats are placed spiral or other springs K, bearing between a nut at the end of 50 shanks l and a shoulder at top of seats k. The heads l' have the projections l² and knobs l³.

The sides of the eaves-trough box are adjusted vertically and horizontally to suit the size of trough to be manipulated, and one end 55 of one trough-section is placed in with its head in groove I and the projections l² are turned over its other edge, whereby it is held tightly in place. Solder is applied and the other section secured thereto.

45

60

I claim—

1. A box for forming eaves-troughs, having sides adjustable vertically and horizontally, substantially as and for the purposes set forth.

2. An eaves-trough box having standards 65 adjustably connected to its bottom and sides adjustably connected to the standards, as and for the purposes set forth.

3. In an eaves-trough box the combination, with the adjustable side C, having the groove 70 I in its inner face, of the adjustable side C', having seats k, catches L, having heads l', projections l², and the operating-spring K, substantially as and for the purposes set forth.

In testimony whereof I affix my signature in 75 presence of two witnesses.

HIRAM G. FILSON.
